UNITED STATES PATENT OFFICE.

HENRY B. CLARKE, OF HIGHLAND PARK, ILLINOIS.

FILING-CASE.

No. 879,944.

Specification of Letters Patent.

Patented Feb. 25, 1908.

Application filed February 20, 1906. Serial No. 302,133.

To all whom it may concern:

Be it known that I, HENRY B. CLARKE, a citizen of the United States, residing at Highland Park, in the county of Lake and State of Illinois, have invented certain new and useful Improvements in Filing-Cases, of which the following is a specification.

This invention relates to improvements in filing cases for card indexes and analogous purposes, and among its salient objects are to provide an expansible card or tablet receptacle, which as it expands effects a shifting movement of each compartment relative to the connected compartments in such manner as to expose a series of index tabs, and as it contracts approaches more and more nearly a right angled rectangular form which can be most conveniently and compactly housed or stored; to provide in conjunction with such an expanding case, mechanism for supporting it in any desired position between its fully collapsed position and fully expanded position; to provide a supporting mechanism of the character referred to which may be shifted or actuated by a foot lever in an extremely convenient manner; to provide in conjunction with such a mechanism a desk-like housing which not only suitably houses the mechanism but forms in fact a desk convenient for writing upon or handling the dockets stored in the filing case; to so construct and support the filing case or cases that it or they may be bodily lifted from the cabinet and stored in a vault or other suitable storage place; and in general to provide a simple, durable and effective mechanism of the character referred to.

The invention consists in the matters hereinafter described, and more particularly pointed out in the appended claims.

In the drawings—Figure 1 is a transverse vertical sectional view of a filing case embodying my invention, the view taken approximately on line 1—1 of Fig. 2 and looking rearwardly; Fig. 2 is a longitudinal vertical section taken on the indirect line 2—2 of Fig. 1 and looking in the direction of the arrows; Fig. 3 is a horizontal sectional view taken on line 3—3 of Fig. 2 and looking downwardly; Fig. 4 is a vertical sectional detail of a carriage mechanism and supporting tracks which supports a shiftable table above the cabinet, as seen in Figs. 9 and 10; Fig. 5 is a detail side elevation of one of the filing cases removed from the cabinet, shown in full lines collapsed and in dotted lines ex-

tended; Fig. 6 is a fragmentary plan detail of the cabinet shown in Fig. 5; Figs. 7 and 8 are details of one of the identifying tabs attached to the upper edge of each compartment; Fig. 9 is a front elevation of a cabinet equipped with a plurality of filing cases and with a shifting table; the central portion of the cabinet being broken out to reduce the height of the figure; Fig. 10 is an end elevation of the parts shown in Fig. 9.

Describing first the device as shown in Figs. 1 to 3, inclusive, 1 designates as a whole a suitable cabinet made to accommodate a single filing case, designated as a whole 2, and inasmuch as the width of the filing case is less than sufficient to insure stability, the sides 3 of the cabinet are constructed to flare outwardly and downwardly from a point below the bottom of the filing case. 75 The cabinet may be made in any preferred or suitable manner, being shown in the present instance as provided with the inclosing sides 3 and ends 4 and 5, respectively, and with a hinged cover 6, which when the filing case is in exposed position, and in use, will be turned over backwardly into the dotted position indicated in Fig. 2.

The filing case 2, as best seen in detail Figs. 5 and 6, consists of a plurality of compartments which are formed by a series of division plates as 9, 9' and 9'' and a series of end plates as 7 and 8; the end plates being connected with each other in pairs by means upper and lower connecting rods 10 and 11. 90 The compartments are alternately shorter and longer so as to telescope upon each other, and the end walls 7 and 8 project forwardly and rearwardly of each division plate, so as to telescope upon each other. The end walls 7 and 8 are made of sufficient width so that when fully extended they still slightly overlap at their edges, as best seen in dotted lines in Fig. 5. In order to effect the expansion of the filing case in such manner 100 that the division plates of the compartments are at all times maintained parallel with each other and upright, and are also caused to shift relatively to each other as the case expands, so as to expose the upper edges of the 105 contents of each compartment and the identifying tablet attached thereto, the several division and end plates are connected together by a series of parallel links 12 and 12'. These links are connected with the compartments in such manner as to extend obliquely 110 downwardly and rearwardly. Commencing

at the front lower corner at each side of the case, short links 12' extend from the front fixed plate connected with the front end plate and are connected with the lower ends 5 of the next or first movable end wall; a second pair of longer links are similarly connected with the fixed end wall and the second movable end wall, and so on, each succeeding pair of links being connected to a succeeding 10 pair of end walls.

In the construction shown the first pair of full length links extend from the upper corners of the fixed end plates at the front rearwardly and downwardly to the fourth movable end plates, and the succeeding full 15 length links extend from the upper ends of the movable end plates in a similar manner to the lower ends of other movable end plates equally distant. The series of successively 20 shorter links at the rear end of the case are connected with the rearmost end wall in a manner exactly the reverse of the series of short links at the front. Each of the longer links is pivotally connected at its center, as 25 indicated at 12", to the corresponding underlying end plate, and in a similar manner those of the shorter links which are long enough to overlap an intermediate end wall are pivotally connected to such intermediate 30 end walls. As a result of the parallel link connections described, expanding movement of the case is necessarily accompanied by a shifting of the succeeding compartments upwardly relatively to the front plate and attached end plates, which in practice are immovably supported, as will now be described.

To this end the front end of the filing case is provided with a bail 13 whereby it may be detachably hung upon the front wall of the 40 cabinet, as indicated in Fig. 2, a bracket-like hook 15 being provided upon the front inner wall of the cabinet for this purpose. At its rear end the cabinet is provided with a similar bail 16 which engages and rests within 45 in a yoke 17 forming one member of the mechanism about to be described. Skeleton bottom supports are provided for the several compartments, these supports being so constructed as not to interfere with the expansion and contraction of the case. To this end two strap-like bars 18 are pivotally connected with the front lower cross bar 11 of the filing case and arranged to extend through suitable apertures in the several 50 back members or partition plates 9 and overlying the remaining cross bars 11, and in a precisely similar way two other bars 19 are connected with the rearmost lower cross bar 11 and arranged to overlie the bars or straps 55 18. The length of each pair of bars is equal to the length of the filing cabinet when collapsed to its shortest dimensions, and when the filing case is expanded these bars slide outwardly upon each other, as indicated clearly in Fig. 5, thus supporting the

contents of the compartments. In addition to the telescoping bars 18 and 19, each end plate is desirably provided with an inturned flange 20 which assists in supporting the contents of the receptacles, the length of 70 these flanges being equal to the width of the compartments when fully collapsed. These flanges 20 may obviously be omitted if desired. Conveniently hooks 21 are provided, one at each side of the filing case, for holding 75 the latter in collapsed form. The upper edge of each division member or back 9 is desirably provided with a tab 22 for designating the contents of the compartment, as shown clearly in detail Fig. 7.

Describing now the mechanism of the cabinet whereby the filing case may be expanded and collapsed while mounted within the cabinet, 23 designates a cross shaft journaled in suitable supports 24 mounted upon the inner side walls of the cabinet and carrying a gear 25 rigid upon the shaft. Upon the same shaft is mounted a small drum 26 around which is wound and secured a strap 27; the other end thereof being extended downwardly to, and connected with, a foot lever 28 at a point intermediate the length of the latter. The foot lever is pivoted at one end to the rear side of the cabinet, as indicated at 29, and projects at its other 95 end out through a suitable vertical slot 30 in the front wall of the cabinet and terminates in a pedal. Adjacent to the shank of the pedal is pivoted a laterally swinging latch 31 provided with a toe-piece 32 whereby it may be moved to engage and hold the foot lever depressed.

33 designates a rack mounted in suitable guides 34 to extend parallel with the direction of expansion of the filing case and intermesh with the rear side of the gear 25. The upper end of the rack 33 carries the yoke 17 hereinbefore referred to, said yoke being rigidly mounted upon the rack.

With the mechanism constructed as described, the expansion of the filing case is effected by simply depressing the foot lever which rotates the gear 25 and thus shifts the rack upwardly through its guides, carrying with it the rear end of the filing case. By means of the latch 31 the foot lever may be locked in any desired position. The collapsing movement of the filing case is effected by gravity, the foot lever being unlatched and the weight of the parts serving to cause 115 the rack to descend and the filing case to collapse.

In Figs. 4 to 10, inclusive, is shown a cabinet which is in its general construction similar to that just described, being made, however, 125 to accommodate a number of filing cases (four as shown) arranged side by side, and each filing case provided with its independent expansion mechanism and corresponding foot lever, as shown clearly in the drawing. 130

As a further feature of improvement I provide a pair of guide rails, as 35, 36 and 37, 38, mounted upon the front and rear sides of the cabinet which serve to support a traveling table, designated as a whole 39. This table or support is shown as of skeleton form comprising parallel end frame straps 40 and 41, and suitable cross connecting bars or straps 42, 43, 44, 45 and 46. From the front lower side of the skeleton table an arm 47 extends downwardly and is then deflected horizontally to form the main frame member of a carriage carrying a pair of wheels 48 which fit between and traverse the track rails 35 and 36. In a substantially similar manner an arm 49 extends downwardly from the rear side of the skeleton table frame and is deflected to form the main frame member of a carriage likewise equipped with wheels 48 which traverse the back rails 37 and 38. These tracks extend the full width of the cabinet, and accordingly the table may be shifted to any desired position along the cabinet, as indicated clearly in Fig. 9.

From the foregoing description it will be understood that I accomplish the several objects of the invention and provide an extremely practical and convenient filing device suitable for general use. An important feature of advantage resides in the convenience with which the filing cases may be lifted out of the cabinet and stored in a vault, as would commonly be done in banking business and under other conditions where the documents filed are of great value. The contents of the filing cabinet are, of course, in no wise disturbed or disarranged, and after the filing cases have been placed in the cabinet they are instantly placed in accessible position by simply shifting them into extended position.

It will be understood that the details of construction and arrangement may be modified without departing from the invention.

I claim as my invention:

1. A collapsible filing case, comprising a series of partition plates, parallel links connecting said plates at each end, each link extending across and connected to the ends of two or more of said plates whereby they are maintained parallel and supported one from the other and a collapsible but substantially inflexible bottom mechanism extending between the several partition plates.

2. A collapsible filing case, comprising a series of partition plates, each provided with side-closure plates arranged alternately in planes out of register with each other so as to overlap, parallel links connecting said plates at each side, each link extending across and connected to the ends of two or more of said plates whereby they are maintained parallel and supported one from the other, and a collapsible bottom mechanism extending between the partition plates.

3. A collapsible filing case, comprising a series of partition plates, a series of corresponding side plates arranged to overlap and telescope upon each other, parallel links connecting said partition plates at each side, each link extending across and connected to the ends of two or more of said plates whereby they are maintained parallel and supported one from the other, and bottom bars connected with the front and rear ends of the case and arranged to slide past each other as the filing case is collapsed, the combined length of each pair of front and rear bars being equal to or greater than the extended length of the bottom of the file. 80

4. In combination, a collapsible filing case comprising a series of vertically disposed partition plates, parallel links connecting said plates at each side and maintaining them in substantial parallelism during their collapsing and extending movements, a collapsible bottom connected with said partition plates, and a supporting mechanism comprising a stationary front member upon which the front end of the filing case is supported and a movable supporting member carrying the rear end of the filing case and guided to move in a direction parallel with the line of expansion of the filing case. 90

5. In combination, a collapsible filing case 95 comprising a series of partition plates and corresponding side plates at each end of each partition plate, parallel links connecting said plates at each side and arranged to effect an expanding and collapsing movement of 100 the filing case in a direction oblique to the vertical, a support arranged to hold the front-end of the case in definite position, and manually - actuated extending mechanism operatively connected with the rear end of 105 the case and operable to extend and collapse the latter.

6. In combination, a collapsible filing case comprising a series of upright partition plates and front and rear end plates, side plates connected with the respective partition plates at each of their ends, a series of obliquely-downwardly and rearwardly extending parallel links connecting said partition and front and rear end plates at each side of the case, each link extending across and connected to the ends of two or more of said plates whereby they are maintained parallel and supported one from the other, a collapsible bottom to said case, a supporting frame, means for 110 fixedly attaching one end of the filing case to said frame, and means for shifting the filing case from collapsed into extended position and vice versa. 115

7. In combination with an expandible filing case, a supporting and operating mechanism therefor comprising a front frame support upon which one end of the filing case may be supported, a rearwardly and upwardly inclined bar mounted to reciprocate in suitable 120 125 130

- guides and operatively connected with the opposite end of said fishing case, a foot lever, and mechanism operatively connecting said bar and foot lever.
5. 8. In combination with an expandible filing case, a supporting and operating mechanism therefor comprising a cabinet, means for attaching the front end of the filing case to the front wall of the cabinet, a rearwardly and upwardly inclined rack bar, guides through which said rack bar is arranged to reciprocate, operative connections between the rack bar and rear end of the filing case, an actuating gear engaging said rack bar, a foot lever and operative connections between the foot lever and gear whereby depression of the foot lever rotates the gear.
9. In combination with an expandible filing case, a cabinet provided with a removable top, a bracket upon the inner front wall of the cabinet to which the front end of the filing case is detachably connected, a rearwardly and upwardly inclined rack bar mounted to reciprocate endwise in suitable guides within said cabinet, a yoke operatively connecting said rack bar with the rear end of the filing case, a shaft, a gear and drum upon said shaft, a foot lever, and a strap operatively connected with the drum and foot lever whereby the depression of the foot lever rotates the drum and elevates the rack bar.
10. In combination with a filing cabinet, horizontally disposed track rails mounted upon the front and rear sides of said cabinet, carriages traversing said track rails, and a table arranged to travel above the cabinet and provided with front and rear leg-extensions connected with said carriages.
11. In combination with a filing cabinet, 40 horizontally disposed pairs of track rails mounted upon the front and rear sides, respectively, of said cabinet, and a shifttable table mechanism mounted to traverse said track rails comprising a frame arranged 45 above the top of the cabinet and provided with front and rear downwardly extending leg-extensions each terminating in a horizontal bar-like extension forming a carriage body and each carriage body provided with a pair of horizontally separated supporting 50 wheels operating and confined between said track rails.
12. A collapsible filing case, comprising a series of partition plates each provided with end-closure plates arranged to overlap each other, connecting said partition plates and parallel links supporting said end closure plates, at each end, each link extending across and connected to the ends of two or more of said plates whereby they are maintained parallel and supported one from the other, a collapsible but substantially inflexible bottom mechanism extending between the partition plates and a supporting mechanism comprising a stationary front member upon 60 which the front end of the filing case is detachably supported, an upwardly and rearwardly shifttable supporting member carrying the rear end of the filing case, and means holding said shifttable member adjustably 70 and rigidly in position.
13. In combination a collapsible filing case comprising a series of vertically disposed partition plates, means flexibly connecting said plates at each side of the case, a collapsible bottom connected with the respective partition plates and a supporting and extending mechanism, comprising a stationary member upon which one end of the filing case is supported, a movable supporting 75 member carrying the opposite end of the filing case, and means guiding said movable supporting member to reciprocate in direct lines and in an upwardly and rearwardly inclined direction.

HENRY B. CLARKE.
